UNITED STATES PATENT OFFICE.

RAY H. MANSON, OF ELYRIA, OHIO, ASSIGNOR, BY MESNE ASSIGNMENTS, TO THE GARDNER MANUFACTURING COMPANY, OF ELYRIA, OHIO, A CORPORATION OF OHIO.

SIGNALING DEVICE.

1,218,099.

Specification of Letters Patent.

Patented Mar. 6, 1917.

Application filed August 14, 1911. Serial No. 643,829.

To all whom it may concern:

Be it known that I, RAY H. MANSON, a citizen of the United States, residing at Elyria, in the county of Lorain and State of Ohio, have invented certain new and useful Improvements in Signaling Devices; and I do hereby declare the following to be a full, clear, and exact description of the invention, such as will enable others skilled in the art 10 to which it appertains to make and use the same.

My invention relates to signaling devices and especially to warning signaling devices, such as are adapted to be employed upon 15 self propelled vehicles to give warning of the approach of such vehicles.

One of the objects of my invention is the production of a device of this character which will embody certain features and improvements. I also aim to produce a device which can be easily manufactured by standard tools and which will be cheap and durable. I also aim to produce a device which 25 will be protected from foreign matter and which can be readily and suitably mounted in a desired position on any of the standard types of such vehicles.

I also aim to make the parts of my device easily assembled, inspected and readily removable for repairs and adjustments, where any one is necessary. In order that the contact carrying member may be readily removed, independently of the armature, I mount the contact carrying member above 35 the armature, providing suitable means to space the two apart. In order that they may be removed together, I connect them to the frame through the same means. I also mount one of the contacts upon a relatively long contact spring, so that the bending may take place through considerable 40 length thereof, since the flexing of a short spring through the range required will cause the spring to weaken and break in a short time.

Other objects of my invention and the invention itself, will be better understood by reference to the following detailed description when taken in connection with the accompanying illustration, showing one specific embodiment of the invention, while the scope will be more particularly pointed out in the appended claims.

Figure 1 is a cross section through a signaling device embodying one form.

Fig. 2 is a detail.

Referring now to the drawing and to the embodiment of the invention there shown, at 1 is shown a casing part, which forms one of the walls of the chamber 2. The part 1 is perforated at 3 for the passage outward of sound waves, which are created inside the chamber. A resonator 4 may be mounted in this opening for the purpose of directing and amplifying the sound waves. This 60 member may be omitted if desired. A sound producing member, such as a vibratile diaphragm 5 is mounted within the chamber. The edge of the part 1 is preferably turned over, as shown at 6. A part 7 forms another 65 wall of the chamber 2. In the form shown this part consists of a cylindrically shaped cup, which is preferably punched from a single piece of sheet metal. The edges of the cup are turned outward at 9, forming 70 an annular flange 8, which is preferably, substantially at right angles to the walls of the cup 7. The sound producing member 5, a vibratile diaphragm, in the form shown, is clamped between this annular flange and 75 the front 1, by some suitable fastening means, such as screws 10. The rear of the cup 7 is perforated, as shown at 11 and an anvil 12, which may be mounted upon the diaphragm, 80 extends through this perforation to the outside of the cup. Means for operating the diaphragm, such as an electromagnet 13 are mounted within the chamber 2, being as shown in the form illustrated, best mounted upon the bottom of the cup on the inside 85 thereof. Studs 14 and 15 are mounted upon the bottom 100 of the cup on the outside thereof. The stud 14 carries the vibratile armature 16 of the electromagnet 13, which is so positioned that when the armature is 90 attracted it strikes the anvil 12, thereby causing the sound producing member to emit sound waves. The stud 15 carries a contact 95 17, which is here shown as adjustable and which co-operates with the contact 18 carried by spring member 19, mounted preferably upon the stud 14. These two contacts constitute an electric switch, which controls the electromagnet 13, the said switch being opened when the magnet is energized and closed when de-energized. By this particular form of structure, I provide a protecting casing for the magnets which are housed away in a safe place, whereas, the contacts and the armature, which from time to time 100 105 110

need attention and adjustment are mounted in a place where they can be easily reached and attended to. A casing 20, preferably a hollow casing, which may be substantially the same diameter as the casing 7, is flared outward at 21 and extended forward at 22, so that one edge fits over the back of the casing part 7. This member when so mounted upon the part 7 serves to protect the armature and the contacts, and at the same time may be readily removed for the purpose of inspection and adjustment.

This particular form of structure is cheap to make, can be readily made with standard forms of tools and with standard shop practice; it is durable, convenient and offers suitable protection to the parts, and, at the same time is handsome and neat in appearance.

Inasmuch as instruments of this type are manufactured as a standard output, it is greatly desired that they should be so made that it will be convenient to mount them in any position upon a vehicle. Some owners desire to mount them upon a side wall and some upon the end wall, or some other position. To meet this demand, I have provided a particular form of bracket, which when combined with my instrument results in an article which will meet such demand. The casing 7 is perforated at 30 and a screw 31 is mounted therein with its head 32 inside the casing. The turn table piece 33 is mounted outside the casing, being keyed to the head of the screw by key 34. A nut 35 holds the turn table piece in position upon the casing. A bracket 36, preferably an angular bracket, is here shown as an S-shaped bracket. This bracket is provided at one end with a wing, preferably a flat wing 37, which is arranged to be fastened to a flat surface; for example, it is perforated at 38 for screws, bolts or other fastening means, with which it may be attached to flat surfaces, though, of course, I may construct this wing of such shape as is best suitable for mounting. The other end of the bracket carries the mounting 40, which is here shown as a cylindrical mounting for the purpose of pivoting the signaling device therein. I prefer to provide this mounting with a web 41 near the center thereof and substantially perpendicular to an element of the walls of the mounting. This web is perforated at 42 for the passage of the screws 31. When mounted upon this bracket, the instrument may be locked in position by suitable locking means, such as a nut 43, which is fastened on the end of the screw. It will readily be seen that this nut 43 may be loosened and the signaling device may be rotated upon the mounting to a desired position and locked there, it being possible to fasten the wing 37 either to the front or side of the car, or to an angularly directed piece and the signaling device then rotated until the resonator is for-

wardly directed, in which position the signaling device may be locked in the mounting.

It will be plain to those skilled in the art that numerous and extensive departures from the form and details of this embodiment of the invention may be made without departing from the spirit of the invention, the same being shown herein solely for the purpose of illustrating one embodiment of the invention.

Having thus illustrated and described a specific embodiment of my invention, what I desire to claim is:

1. In a signaling device, the combination of a sound producing device, a plurality of parts forming the walls of a chamber in which said sound producing device is mounted, one of said parts being cup-shaped and having the edge of said cup turned over to form an annular flange theron, another of said parts having an opening therein for the passage of sound waves and having its edge folded back over the turned over edge of the first named part, means passing through the edge of the sound producing device for connecting said parts and device together, means to actuate said sound producing device mounted on the back of said cup-shaped member, operating means for said actuating means mounted in said chamber on the bottom of said cup-shaped part, controlling means for said operating means mounted on the outside of said cup-shaped part and a cover for said controlling means.

2. In a signaling device, the combination of a sonorous member, a plurality of parts of said device forming the walls of a chamber, one of said parts being a cup-shaped member with its edges turned outward to form an annular flange upon which said sonorous member is mounted, a second part perforated for the egress of sound waves having its edge folded back over the turned outward edge of the cup-shaped member, means passing through the edge of the sonorous member to connect said sonorous member and parts together, controlling and actuating means for said member mounted on the outside of the bottom of said cup-shaped part and operating means for the actuating means mounted on the inside of the cup-shaped part and a cover for the mechanism mounted on the outside of said chamber.

3. In an automobile horn, the combination of a sonorous diaphragm, a magnet to operate said diaphragm, a cup shaped punching upon the bottom of which said magnet is mounted within the cup, an annular flange upon the outside edge of the mouth of said cup, connected to said sonorous diaphragm, means passing through the edge of the diaphragm for connecting said parts and diaphragm together, a second punching having its edge folded backward

over the annular flange of the cup-shaped punching and being provided with an opening for the egress of sound waves, an anvil on said diaphragm extending through the 5 bottom of said cup and projecting beyond, an armature on the bottom of said cup on the outside thereof, switch contacts mounted on the outside of the bottom of said cup and controlled by said armature and a second 10 cup shaped punching covering said armature and said switch contacts.

4. In a device of the class described, the combination of a vibratile diaphragm, a plurality of parts of said device forming the 15 walls of a chamber for said diaphragm, a cup shaped punching forming the rear and side walls of said chamber, the bottom of the cup being perforated and forming the rear 20 wall of the chamber, the edge of the mouth of the cup being turned outward forming an annular flange thereon, a front wall of said chamber having a perforation therein for the passage of sound waves therethrough and having its edge folded backward over 25 the annular flange, said diaphragm being clamped between said front and said flange leaving the central part of the diaphragm free to vibrate, means passing through the 30 edge of the diaphragm for connecting said parts and diaphragm together, an anvil mounted on the center of said diaphragm and extending through the opening in the bottom of the cup, electro-magnetic means 35 for operating said diaphragm mounted inside said cup and on the bottom thereof, an armature adapted to be vibrated by said magnetic means and when so vibrated, to strike said anvil, said armature being mounted on the bottom of said cup on the outside 40 thereof, electric switch contacts mounted on the outside of the bottom of said cup and

controlled by said armature and a second cup normally covering the apparatus mounted on the outside of the bottom of said cup.

5. In an automobile horn, the combination of a vibratile diaphragm, a plurality of parts forming a chamber for said diaphragm, one of said parts consisting of a cup-shaped punching having openings in the bottom and having the edge of its mouth turned outward to form an annular flange substantially at right angles to the walls of the cup, a second part having an opening therein to permit the egress of sound waves, said diaphragm being clamped between said two 55 parts, means to space said diaphragm from said second part, means to clamp said two parts, said diaphragm and said spacing means together, the edge of said second part being bent rearward and extending over the 60 edge of said flange, an electro-magnet mounted inside of said cup-shaped part and attached to the bottom thereof, an anvil on said diaphragm extending through an opening in the bottom of the cup-shaped part, a 65 stud on the bottom of said cup mounted on the outside thereof, an armature adapted to be attracted by said magnet to strike said anvil, a spring connecting said armature to said stud, a spring connected at one end to 70 said stud and resting at the other end against said armature, a contact carried by said spring, a second contact and a bridge mounted on the bottom of said cup-shaped 75 part carrying the second contact.

In testimony whereof, I affix my signature, in the presence of two witnesses.

RAY H. MANSON.
